WINDOW DRAPE DUST CATCHER

Filed March 27, 1931

INVENTOR,
William Roslyn.
BY
David E. Lain,
ATTORNEY.

UNITED STATES PATENT OFFICE

WILLIAM ROSLYN, OF BELLINGHAM, WASHINGTON

WINDOW-DRAPE DUST CATCHER

Application filed March 27, 1931. Serial No. 525,669.

My invention relates to improvements in window-drape dust catchers, and has for an object to provide a removable shelf to substantially close the opening between the usually offset window curtain rods and the window casing to catch and retain any dust being carried by downward air currents hitherto passing through said opening.

Another object of my improvement is to provide a frame suitable to be covered by cloth for said shelf.

Another object of my improvement is to provide means of adjusting said frame to the width of different windows.

Other objects of my improvement will appear as the description proceeds.

I attain these and other objects of my improvement with the device illustrated in the accompanying sheet of drawings in which Figure 1 is a plan view of the shelf frame, Fig. 2 is a plan view of one of the telescoping ends of the shelf frame, Fig. 3 is a plan view of the top edge of a window casing with the usual curtain rods and draperies attached and showing my dust-catching shelf in place therewith, and Fig. 4 is an end elevation of Fig. 3 in section on the line 4—4 thereof.

Similar characters refer to similar parts throughout.

With more particular reference to the designated parts: A central part of the frame consists of two tubes 5, 5 fastened together in the same plane by bridges 6, 6, 6 and disposed in parallel relation. An end portion of the frame is shown separately in Fig. 2 and consists of a rod bent in U shape having legs 7, 7 retained parallel by bridges 8, 8 fastened thereto and disposed for extension in the ends of tubes 5, 5 as shown in Fig. 1, which illustrates the frame in full lines when extended to nearly its maximum length and in dotted lines when withdrawn to its minimum length. Rods 7 make a sufficiently close fit in tubes 5 to require a little force to move them therein.

When the frame is covered by cloth my shelf is completed. By preference the cloth cover is made in a suitable sleeve 9 into which the frame is extended through open end a9, and flap b9 on the sleeve end is extended from

its open position at b9' into opening a9 to its closed position at b9 where it covers the end of the frame.

Top flange 10 of a window casing has curtain rods 13, 13 fastened thereto as shown in Fig. 3 and draperies 14, 14 hung over said rods, providing opening 15 between the rods and casing flange. Particular brackets 12, 12 are fastened to casing flange 10 disposed to retain shelf 9 within opening 15 and about 60 in the plane of rods 13 to substantially close said opening. Thus is completed the mounting of my dust-catching shelf in place.

Especially during the artificial heating of living rooms a definite circulation of the air in the rooms is set up which in general rises from near the floor centrally in the rooms spreads across and beneath the ceilings thereof and descends to the floor near the walls thereof. Because of the cooler areas provided by the glazed windows air circulation down by the same is more rapid than in other parts of the rooms, resulting in loading the draperies therat with dust from said air circulation. More especially where curtain rods shaped as shown at 13 are used, providing opening 15, my shelf is well suited to catch dust from said descending currents of air and thus protect the draperies therefrom. And even when the straight curtain rods of 80 earlier times are used they also are offset from the window casing providing an opening therebetween through which air currents may pass with their load of dust, my shelf, as disclosed, is well adapted to close such openings catch the dust in said air currents and the draperies are protected from discoloration and injury.

When it is desired to wash the shelf covering 9 it is easily removed from the frame for this purpose. This cloth frame cover may be of any kind and texture desired and will usually correspond in color with the draperies which it is used to protect.

Having thus disclosed my invention, what I claim as new therein and desire to secure by Letters Patent is,—

The extendible frame of a window shelf including a central portion consisting of paral-

lel tubes spaced apart by bridges fastened thereto, and two end portions of said frame each consisting of a U shape rod the legs of which are fastened apart by intervening bridges disposing said legs to simultaneously enter the adjacent ends of said central portion of the frame.

WILLIAM ROSLYN.
